PAUL EDMUND GAIRE, OF NEW YORK, N. Y.

HAIR TREATING APPARATUS

Application filed August 5, 1931. Serial No. 555,289.

This invention is directed to an improvement in apparatus for use in curling human hair, being particularly directed to the provision of a sectional box in which the hair coiled on a coiling rod is arranged during treatment, each section of the box being provided with a relatively fixed hair-clamping member to clamp the hair between the box and the head of the user and serve to protect the head from the heat of the box incident to the hair treating operation.

In apparatus of this type, it has been heretofore proposed to provide sectional boxes in which the hair coiled on a coiling rod is retained during treatment and independent clamps to grip the hair between the box and head and protect the head of the customer against the heat of the box; and it has been further proposed to provide clamping means of this type with which the coiling rod or pin is more or less fixedly associated following the coiling of the hair, with the heating box thereafter applied as an independent element. These constructions, while serviceable for the purposes for which they are designed, require a number of independent operations to apply the clamp and then position the heating box, with the result that the clamp and heating box are not at all times relatively associated in the best positions to accomplish the effective result, that is, the curling of the hair close to the scalp.

The present invention is directed primarily to simplifying the operation by applying the clamp and curling box in order that through the improved construction these elements are brought into effective cooperative relation to the head of the user in substantially a single operation, and furthermore the present invention seeks to so combine the box and clamp as to insure that when these parts are in position on the head of the user, the relation of the clamp and box will be such as to permit the most effective close curling of the hair and insure at all times the desired close relation of the clamp to the scalp of the user and the curling box in proper fixed relation to the clamp.

In carrying out the object of the invention, the heating box heretofore made in sepa-

ral sections connected for swinging or pivotal movement is provided with a fixed section of the clamp, the relation of the clamp sections and box sections being such that when the box is closed the clamp sections are 55 in intimate clamping relation on the hair between the box and scalp of the user. Furthermore, the structure contemplates independent fastening means for the box sections and for the clamp in order to insure that each 60 will have its proper cooperation and function in its use in the hair curling process.

The invention is illustrated in the accompanying drawings, wherein:—

Figure 1 is a perspective view showing the 65 combined box and clamp, the parts being shown in closed positions.

Figure 2 is a transverse sectional view of the same.

Figure 3 is a perspective view of the respective sections of the combined box and clamp shown separated.

Figure 4 is a broken bottom plan view showing the clamp, with the sections thereof in clamping relation.

Figure 5 is a transverse sectional view 75 through a combined box and clamp showing a somewhat modified construction.

The box of the present invention is of more or less conventional type, embodying two 80 semi-circular sections 1 and 2 having semi-circular end walls 3 so that when the sections 1 and 2 are formed in mating relation, an elongated, circular closure is provided in which the conventional or any appropriate 85 form of pin or rod on which the hair is previously curled is housed for the subsequent treatment. Each section 1 and 2 is formed on one longitudinal edge with a more or less diametrically extending ear 4 formed with 90 an elongated opening 5, the ears registering when the sections are assembled and providing, through the medium of a wire length arranged in coil form at 6 through the registering openings 5 of adjacent ears, a hinged connection on which the sections 1 and 2 may be widely opened.

The sections 1 and 2 are formed with outstanding, tubular extensions 7 and 8 preferably arranged in longitudinally offset rela-

tion and terminally providing for the connection of a flexible tube. The tubular extensions 7 and 8 open through the walls of the respective sections to provide for the appropriate treatment of the contained hair as, for example, steam may be introduced through one of the connections as 7 and cool air through the other in accordance with the treatment to be given the hair. Obviously, of course, these tubular projections may be used for any appropriate character of treatment of the hair.

Ordinarily steam is used in connection with the hair treatment, and hence it is important that the meeting edges of the sections 1 and 2 be sealed against steam leakage and the sealing means must be such as to permit passage of the hair between the sealing means without interrupting the sealing effect.

To secure the sealing cooperation with the sections, each section is provided with an endless band 9 which overlies and cooperates with the meeting edges of the sections. This band 9, preferably of soft rubber, is channeled at 10 to receive the appropriately formed edges 11 of the sections so that the band is practically forced into cooperation with the edges of the metallic sections and when in place is held against casual separation by its own 20 gripping cooperation with the edges of the section.

The respective bands 9 thus form a layer of appropriate thickness of compressible sealing material throughout the full free edge of each section 1 and 2 so that when the sections are brought into box-forming relation, the proximate faces of these sealing bands are compressed, with the result of providing an effective seal against leakage from the interior of the box. The relation of the sealing elements, when the box sections are in closed position, is illustrated more particularly in Figure 2.

In order to insure a sufficient relative pressure of the respective bands for effective sealing, the sections are held in box-forming relation under a clamping means arranged at each end of the box and functioning, when in operative positions, to draw the sections together with considerable pressure. The clamping means includes a plate 12 pivotally supported at 13 on the end walls 3 of one section, each plate being extended in the form of a finger piece 14 whereby the plate may be swung on its pivot.

Pivotally carried in the plate beyond the pivot 13 of the plate is a yoke 15, the cross bar 16 of which is arranged to engage with an appropriate keeper 17 on the end wall of the other section of the box. Obviously, with the cross bar 16 of each yoke engaged with the keeper 17, the swinging of the plate 12 on the pivot 13 by means of the finger piece 14 so as to carry the pivotal connection of the yoke with the plate inwardly of the

line joining the pivot 13 and keeper 17 serves to draw the sections into clamping cooperation with considerable pressure and at the same time maintain a lock, preventing separation of the sections until the finger piece 14 is swung in the opposite direction. The arrangement of the parts is such that the finger piece, when in locking position, overlies one of the semi-circular walls of a section in order to avoid undue projection beyond the box, the end of the finger piece being, however, slightly spaced from the outer surface of the wall of the section in order to provide for convenient manipulation of the finger piece in the release of the locking means.

As understood in this type of apparatus, the hair is coiled about a pin, indicated at 18 in Figure 2, and the hair between the pin and head of the user passes between the sealing bands 9 and the relatively lower portion of the box, it being understood that the box is closed about the pin to permit the hair on the pin to be subjected to the desired treatment within the box. It has been found that under conventional treatment, there is an appreciable heat which, to say the least, might prove inconvenient to the person whose hair is being curled, and furthermore the hair immediately adjacent the scalp must be clamped to insure an effective holding of the parts against undue strain and particularly prevent any pulling of the hair during the rolling or arrangement within the box from being felt by the person whose hair is being treated.

It has been heretofore proposed to provide an independent clamp which grips the hair close to the head of the customer, preventing pulling strain on the hair from affecting the customer, with the clamp further provided with means to prevent the heat from the box from reaching the head of the customer. Heretofore, the clamp and box have been arranged as separate and independent elements, and while it is recognized that a close curl is desirable, the independence of these elements, except under extreme care of the operator, does not tend to the production of a close curl because they may be separated relatively at different distances. Attempts have been made to overcome this objection by providing on the clamp a means by which the curling pin 18 may be fixed in predetermined relation to the clamp, thus tending to maintain the close curl desired. However, the objection to this type of apparatus is that the curling pin is not always properly rolled for the curling of the hair when applied to the clamp, and it is essential that the clamp be fixed in position before the hair is curled, thus necessitating several distinct operations because after the hair is rolled on the pin and the pin is applied to the clamp, the box has to be later applied in position.

The present invention seeks to overcome these difficulties by combining with the box a clamp in order that the most effective relation for a close curl may be had and all parts associated in a single operation. To secure this result, and in the form illustrated particularly in Figures 1 to 4, the clamp is made up of bars 19 and 20, preferably of non-heat-conducting material, as asbestos or the like, and these bars are provided with rubber sheaths 21 which completely envelop the bars transversely but which terminate short of the ends of the bars, leaving projecting portions 22 of the respective bars beyond each end of the sheath enveloping that bar. One of the sheaths, preferably on the side carrying the tubular extension through which steam is admitted, is extended in the form of a flexible flap 23 to cover a broader area of the scalp of the person being treated and thus afford a larger protection against the heat of the box.

The sheaths 21 are preferably of soft rubber and the edges of the respective sheaths designed for clamping contact, as will later appear, are formed for more effective gripping of the hair in providing that one of such meeting edges shall be convex, as at 24, and the other of such meeting edges shall be concave, as at 25, to thereby more effectively grip the hair strands passing therebetween. The clamping elements 19 and 20 are arranged in the same horizontal plane immediately beneath the box and each of these clamping sections is more or less rigidly connected to one of the box sections. For example, section 19 is secured directly to section 1 of the box, while clamping section 21 is secured directly to section 2 of the box.

This securing means may be of any preferred nature as, for example, a pin 26 or other like means may be passed through the exterior portion of the sealing band 9 and through the appropriate clamping section to be connected to that section of the box, the pin thus rigidly fixing the clamping section to the corresponding box section. Of course, the pin 26 does not pass through the lower portion of the sheath of the clamping section, as otherwise an objectionable contact with the scalp of the person may result. The pins 26 are intended to indicate diagrammatically any appropriate metallic securing means for fixing a clamp section to one of the box sections.

The clamping sections 19 and 20 are designed to have independent fixing means through the provision of levers 27 pivotally secured at 28 to one section and formed with openings to embrace the other section. These levers 27 may be in the form of plates having returned bends 29, with the free ends pivotally connected and the plates spaced apart so that the return band provides a means for embracing the other clamping section when

such sections are in clamping relation. If desired, the free end of the plate may be laterally extended, as at 30, to provide a finger piece for the convenient operation of the lever.

With the hair coiled on the pin 18 to a position close to the head of the person, the box sections are arranged to embrace this pin with the hair curled thereon and the sections are closed and locked by the clamping means described. In this closing of the sections, the clamping members 20 and 21 are also brought into clamping cooperation, the hair between the pin 18 and the head of the person being treated passing between the clamping bands 9 and the lower edges of the box and between the relatively concave and convex edges of the sheaths of the clamping members. After the box sections have been secured, the clamping levers 27 of the clamp may be operated to further compress the clamping members relatively.

Of course, the arrangement is such that the clamping members are practically in contact with the scalp of the person being treated so that a relatively short section of hair extends between the scalp and pin. By the combination of the box and clamping members and their relative positioning in a single operation, there is very much closer curling permitted and at the same time the relation of the box and clamp in the best possible arrangement is secured because the clamp occupies the closest possible position to the box and this relation is maintained under any and all conditions by reason of the fact that the box and clamp are in effect a single element. Of course, the clamp not only acts to clamp the hair close to the head of the user, but also serves to prevent the transfer of heat from the box to the scalp.

In Figure 5, I have illustrated a modified arrangement in which the lower sections of the sealing band for the box are integrally formed to provide the clamping elements. In this figure the box sections, indicated at 31 and 32, are similar to the sections previously described in form and are designed to be locked in the same manner. The sealing elements, indicated in the preferred form at 9, are here shown as bands 33 which cooperate with the edges of sections 31 and 32, as in the preferred form. In this form, however, the lower sections of the bands 33 are extended beyond their normal width to provide clamping elements 34 and 35. These elements on their proximate edges are formed with relatively concave and convex meeting edges, as 36 and 37, and are preferably extended laterally to define protective flaps 38.

In the modified form, as well as in the preferred form, it is apparent that the clamping cooperation is carried out simultaneously with the closing of the box sections, and

while the modified form provide no particular means for additionally securing the elements of the clamp together, as is provided in the preferred form, it is nevertheless apparent that due to the resilient nature of the clamping members of the modified form, there will be a clamping cooperation through the mere provision of locking the box sections together.

10 I claim:—

1. In a hair curling apparatus, a sectional heating box of hollow form to receive the hair curling pin, and clamping members, said members being respectively secured to and movable with the box sections.

2. In a hair treating apparatus, a treating box made up of separable sections, means for clamping the sections of the box together, and hair clamping members respectively secured to and movable with the box sections, the meeting edges of the clamping members presenting a curved clamping cooperation.

3. In a hair curling apparatus, a sectional box, clamping members respectively secured to and carried with the box sections, means for locking the box sections together, and means for independently securing the clamping members in clamping cooperation.

4. In a hair treating apparatus, a sectional box, means for clamping the sections together, clamping members respectively secured to and carried by the box sections, said clamping members being moved into clamping cooperation in the closing movement of the box sections, and means on the clamping members for additionally securing the clamping members together.

5. In a hair treating apparatus, a sectional box, a flexible sealing member for the meeting edges of the box sections, means for clamping the box sections together to insure sealing contact with the sealing members, and clamping elements adapted to clamp the hair between the box and the scalp of the user, said elements being secured respectively to the sealing members of the box sections.

6. In a hair treating apparatus, a sectional box, a flexible sealing member for the meeting edges of the box sections, means for clamping the box sections together to insure sealing contact with the sealing members, clamping elements adapted to clamp the hair between the box and the scalp of the user, said elements being secured respectively to the sealing members of the box sections, each clamping member embodying a length of heat-resisting material, and a protective sheath for said heat-resisting material.

7. In a hair treating apparatus, a sectional box, a flexible sealing member for the meeting edges of the box sections, means for clamping the box sections together to insure sealing contact with the sealing members, clamping elements adapted to clamp the hair between the box and the scalp of the user, said ele-

ments being secured respectively to the sealing members of the box sections, each clamping member embodying a length of heat-resisting material, a protective sheath for said heat-resisting material, and cooperating clamping means carried by the lengths of heat-resisting material.

8. In a hair treating apparatus, a sectional box, a flexible sealing member for the meeting edges of the box sections, means for clamping the box sections together to insure sealing contact with the sealing members, clamping elements adapted to clamp the hair between the box and the scalp of the user, said elements being secured respectively to the sealing members of the box sections, each clamping member embodying a length of heat-resisting material, a protective sheath for said heat-resisting material, and cooperating clamping means carried by the lengths of heat-resisting material, one of said sheaths being extended as a protective flap.

9. In a hair treating apparatus, a sectional box, means for clamping the sections together, sealing bands interfitting with the meeting edges of the sections to seal their juncture when the box is closed, clamping elements respectively secured to the sealing bands of the sections, the clamping members being arranged to be moved into clamping cooperation in the closing movement of the box, means for holding the box sections in closed sealing relation, and independent means for holding the clamping members in clamping cooperation.

100 In testimony whereof I affix my signature.
